Primary Examiner — Randall Gholson*(74) Attorney, Agent, or Firm* — Lowe Graham Jones PLLC(57) **CLAIM**

The ornamental design for a reflective strip, as shown and described.

DESCRIPTION

FIG. 1 is a front view of the reflective strip.

FIG. 2 is a top view of the reflective strip.

FIG. 3 is a left side view of the reflective strip.

FIG. 4 is a right side view of the reflective strip.

FIG. 5 is a bottom view of the reflective strip.

FIG. 6 is rear a view of the reflective strip; and,

FIG. 7 is a perspective view of the reflective strip, shown in a preferred environment in which the reflective strip is folded in half and clipped to a pocket of a representative shirt or other article of clothing.

The broken lines depict portions of the reflective strip that form no part of the claimed design. The broken lines showing a pocket in FIG. 7 illustrate a preferred environment and form no part of the claimed design.
